UNITED STATES PATENT OFFICE.

ELMER F. WIEBOLDT, OF CHICAGO, ILLINOIS.

DUPLEX CASHIER'S DESK.

1,107,735.

Specification of Letters Patent. Patented Aug. 18, 1914.

Application filed May 3, 1913. Serial No. 765,245.

To all whom it may concern:

Be it known that I, ELMER F. WIEBOLDT, a citizen of the United States, residing at Chicago, in the county of Cook and State of Illinois, have invented a certain new and useful Improvement in Duplex-Cashier's Desks, of which the following is a specification.

My invention relates to desks intended for cashiers' use especially under circumstances where different cashiers are to use the same desk at different periods of the day.

It will be understood that in busy mercantile establishments and like places where a cashier must attend steadily at the cashier's desk, it becomes necessary from time to time to relieve one cashier and put another in his or her place. It is not desirable to mix the accounts of the two cashiers as this would virtually make one sponsor for the accounts of the other and yet it is usually inconvenient, if not, impractical, to provide two separate desks.

The object of my invention is to provide a construction such that a single desk may be utilized by two different cashiers and yet keep the papers and cash handled by the respective cashiers separate.

In my desk there is a separate drawer and a separate cabinet compartment for each cashier and the drawer and compartment of one cashier may be locked without interfering with the drawer or compartment belonging to the other cashier. Furthermore, in my desk the locking of one compartment of the cabinet automatically locks the corresponding drawer. The compartment of one cashier is locked up so long as the drawer and compartment of the other cashier is open.

In connection with these general objects it is my purpose to provide certain details of construction rendering the desk convenient, compact and safe, said details being hereinafter more particularly described and claimed.

I accomplish my objects by the mechanism illustrated in the accompanying drawings in which—

Figure 1 is a front elevation of a desk embodying my invention. Fig. 2 is a sectional side elevation. Fig. 3 is a plan section on the line 3—3 of Fig. 1. Fig. 4 is a plan section on the line 4—4 of Fig. 1. Fig. 5 is an isometric perspective of the preferred form of cash till. Fig. 6 is a sec-

tional detail of the drawer-locking device, the section being taken on the line 6—6 of Fig. 2. Fig. 7 is a bottom plan view of the parts shown in Fig. 6.

Similar numerals refer to similar parts throughout the several views.

Referring to the drawings, the top 1 of the desk has mounted thereon a duplex cabinet comprising the back 2, side walls 3 and 4, central partition 5, top 6 and door 7. Said partition divides the cabinet into two compartments *a* and *b* and the door 7 is hinged at the front of partition 5 in such manner that when the door is closed in one position it will leave compartment *a* closed and compartment *b* open (as in Fig. 3), and when swung to closed position in front of compartment *b*, it will close compartment *b* and open compartment *a*. Compartments *a* and *b* are designed for the filing of sales slips or other papers which the cashiers are required to handle pursuant to their duties, and while the filing devices may be varied, I show them in the form of spindles *a'* and *b'*. The spindles *a'* are secured to the back 2 in compartment *a* and to that side of door 7 which faces compartment *a*. Similarly the spindles *b'* are some of them mounted upon the wall 2 in compartment *b* and others upon that side of the door 7 which faces compartment *b*. In consequence when the door is closed as in Fig. 3 all the spindles *a'* will be inclosed and all of the spindles *b'* will be exposed and accessible.

The body of the desk below top 1 embraces back 10 and sides 11 and 12. Within the body of the desk are horizontal guides 13 for supporting the cash drawers A and B. These drawers are arranged side by side, the drawer A occupying the space beneath the cabinet *a* and the drawer B occupying the space beneath the cabinet *b*. By preference these drawers are each provided with guides 15 for supporting cash tills 16 (see Figs. 2 and 5).

The desk is provided with a drawer-lock which in the form selected to illustrate the invention consists of a rod 18 secured to the bottom of door 7 by a plate 19 or other suitable fastening device. Said rod is concentric with the axis of rotation of the door and extends down between the cash drawers A and B as best shown in Figs. 4, 6 and 7. At the lower end said rod carries a locking arm 20 which extends horizontally below the

bottom of the drawers in such manner as to engage either the stop 22 extending down from the bottom of drawer A or the stop 23 extending down from the bottom of drawer B. Locking arm 20 extends in the same direction from the axis as does the door 7 and hence said arm will always lock the door beneath the closed compartment of the cabinet above. In other words when compartment a 10 is closed, the drawer A will be locked while compartment b will be open and the drawer B unlocked.

Means are provided for locking door 7 in each of its closed positions. For this purpose I provide locks 25 and 26, one for holding the door closed in one position, and the other for holding the door closed in the other position. Preferably the key holes of these locks open on opposite faces of the 20 door.

In use each cashier will have his own individual key. For illustration, let it be assumed that the principal cashier will use compartment a and drawer A, and the assistant cashier will use compartment b and drawer B. The principal cashier will be provided with a key for lock 25 and the assistant with a key for lock 26. When the time comes for the assistant to relieve the 30 principal cashier, the principal will turn the key in lock 25 and lock the door 7 in the position shown in Fig. 3, leaving compartment b open and compartment a closed. The locking of the door in this position will 35 rotate the locking rod to such a position that the arm 20 will engage the stop 22 on the drawer A and hold the latter securely locked. Thus the principal cashier may leave and at the same time have the assurance that neither the assistant nor other persons will be able to meddle with the contents of that portion of the desk used by the principal. All assurances are reciprocal for 40 when the principal returns and relieves the assistant, the assistant by using his key may lock his compartment and drawer against access by any person other than himself. By thus rendering the desk duplex, two persons may safely use the same desk and consequently space is required for only one 45 desk where otherwise two desks would be required. Furthermore, it is possible to utilize both faces of the door for filing purposes. At night, of course, and out of 50 business hours the cash and papers will all be removed, or the assistant may turn his cash and papers all over to the principal to be locked in the parts used by the principal.

Having thus described my invention, what 60 I claim as new and desire to secure by Letters Patent is:—

1. A cashier's desk provided with a cabinet having two compartments, a door hinged to the cabinet and adapted to close one compartment and expose the other when closed

in one position and to expose the first and close the second compartment when closed in another position, a pair of drawers and a locking device capable of occupying two positions and adapted when in one position 70 to lock one drawer and release the other and when in another position to release the first and lock the second drawer, said locking device being operated by said door.

2. A cashier's desk provided with a cabinet having two compartments, a swinging door hinged to the cabinet in position to close one or the other of said compartments, two parallel drawers, a locking rod rigidly secured to said door and adapted to engage 80 one or the other of said drawers depending upon the position of the door.

3. A cashier's desk consisting of a top and a suitable support therefor, said desk being provided with a cabinet mounted upon the 85 top of the desk and divided into two compartments, a swinging door hinged upon a vertical axis to the cabinet in position to close one or the other of said compartments, two drawers located beneath the top of the 90 desk and a locking rod rigidly secured to the door and passing down to the drawers and having an arm adapted to engage one or the other of said drawers depending upon the position of the arm and of the 95 door by which the arm and locking rod are operated.

4. A cashier's desk consisting of a top and a suitable support therefor, said desk having an open front cabinet, a vertically 100 arranged partition dividing the cabinet into two compartments, a swinging door hinged at the front of said partition and adapted to close one or the other of said compartments, drawers slidingly mounted in said 105 desk, stops on said drawers and a locking rod having an arm adapted to swing into the path of one or the other of said stops for locking the respective drawers, said locking rod being rigidly secured to and operated 110 by said door.

5. A duplex cashier's desk consisting of a top and a suitable support therefor, said desk having an open front cabinet mounted upon the top of the desk, a vertically arranged partition dividing the cabinet into two substantially equal compartments, a swinging door hinged at the front of said partition and adapted to close one or the other of said compartments, drawers slidingly mounted in the desk beneath the top thereof, stops on said drawers, a locking rod fastened to and rotatable with the door, said rod being located between said drawers and a horizontal locking arm rigid with said rod and adapted to engage the stop upon one or the other of said drawers.

6. A cashier's desk having two drawers, a rotatable locking rod adapted to engage one or the other of said drawers to lock the 130

same, a cabinet, a partition dividing said cabinet into two compartments, a swinging door hinged at the front of said partition and adapted to close one or the other of said compartments, said door and said locking rod being rigidly secured together, whereby the rod may be operated by the door, and two locks, one for locking the door in one closed position and the other for locking the door in the other closed position.

7. A cashier's desk having a cabinet, a partition dividing said cabinet into two compartments, a swinging door hinged at the front of said partition and adapted to close one or the other of said compartments, two parallel drawers, a locking device operated by said door and adapted to engage one or

the other of said drawers depending upon the position of the door, and two locks carried by said door, one of said locks being 20 adapted to lock the door in one of its closed positions and the other of said locks being adapted to lock the door in the other of its closed positions, each lock thereby causing the door and one of the drawers to be 25 locked.

In witness whereof, I have hereunto subscribed my name in the presence of two witnesses.

ELMER F. WIEBOLDT.
